UNITED STATES PATENT OFFICE.

EDWARD J. BRANDT, OF WATERTOWN, WISCONSIN, ASSIGNEE TO BRANDT CASHIER COMPANY, OF CHICAGO, ILLINOIS, A CORPORATION OF ILLINOIS.

COIN-DELIVERY CHUTE.

1,266,099.

Specification of Letters Patent. Patented May 14, 1918.

Application filed April 10, 1916. Serial No. 90,214.

To all whom it may concern:

Be it known that I, EDWARD J. BRANDT, a citizen of the United States, and resident of Watertown, in the county of Jefferson and 5 State of Wisconsin, have invented certain new and useful Improvements in Coin-Delivery Chutes, of which the following is a specification.

My invention relates to coin paying machines and has particular reference to a 10 novel delivery chute.

An object in the present invention is to provide a multiple coin runway for the purpose of gathering coins of various denominations as they are discharged from a coin paying machine, turning said coins on edge and deflecting their course so that at the 15 delivery end of the said runways they are converged to one point, to the end that the 20 miscellaneous coins may all be delivered at that point. This delivery may be made directly onto a counter or into a receiving receptacle. Provision is made in the device as at present constructed for discharging 25 two coins into the same runway, and in order that the coins may not tilt to one side due to the necessity for making a chute of the width of at least two coins, I provide for two levels in the runway. While the 30 runway is wide enough for two coins, the space alongside the upper runway is only wide enough for one coin. When two coins are discharged into the runway at the same time one will run upon the upper level and the 35 other upon the lower level until one coin is ahead of the other, whereupon it will drop to the lower level. Another feature of this runway is that it is possible to gather the coins at one point and yet always to determine 40 that the same denomination of coins runs into a given section of the runway which is an advantage for distribution in a compartment receptacle. It is possible by the use of the present arrangement to count 45 multiples of coin by depressing a single key without mixing the coins of different denominations; for instance, it would be possible to count a half dollar, quarter, two dimes and a nickel with each depression of 50 the split dollar key and yet delivering coins into the compartment receptacle, the coins being kept separate according to their denomination without the necessity for separating the same after counting.

55 A further advantage of the present con-

struction is its adaptability to paying machines as they are at present on the market without material changes at the delivery end.

The invention will be more readily understood by reference to the accompanying drawings, wherein—

Figure 1 is a plan view of a distributing and delivering device such as contemplated by me;

Fig. 2 is a sectional view on the line 3—3 of Fig. 1;

Fig. 3 is a sectional view on the line 3—3 of Fig. 1;

Fig. 4 is a section on the line 4—4 of 70 Fig. 1;

Fig. 5 is a plan view of a slightly modified form of a coin-receiving cup, and

Fig. 6 is a section on the line 6—6 of 75 Fig. 5.

The structure of my invention includes a frame 10 providing pockets 11 for the accommodation of the feet or supporting members of a change-making machine 12, such as is shown in dotted lines in Fig. 2. 80 Mounted on the frame are four pairs of double runways 13, 14, 15, 16, thus providing a runway for silver dollars, half dollars, quarters, two runways for dimes, one runway for nickels and two runways for pennies. As shown, the runways are inclined, the coins being maintained in edgewise position and allowed to roll down the chutes or runways by gravity. Disposed in proper relation to the change-making machine are a 90 plurality of hoppers numbered 17 to 24 inclusive, as best shown in Figs. 1 and 3. The mouths of these hoppers are narrow, that is, they are not of sufficient width to permit the coin to pass therethrough in any position except that which will cause the coin to fall in edgewise position into the respective runway thereunder. In other words, by the shape of the hopper the coins are caused to enter the runways in the proper position. 95 The exact structure of hoppers is unimportant, but in the present instance it will be seen that I have combined the 8 hoppers in one structure which is adapted to be secured to the face of a change-making machine by means of the screws 25. By the addition of this hopper member and the runways any of the change-making machines of this type now on the market may be converted into one of the type herein disclosed, 105 110

in which the coins are selected and kept separated to the point of delivery, where they may be combined or delivered into separate compartments.

5 Certain of the runways, for example, the ones lettered 13^a and 14^a in Fig. 3, must be arranged to accommodate two coins, as is necessary when four pennies are paid. In this case two pennies are delivered through 10 each of the runways mentioned. To avoid the possibility of coins lodging in these runways because of leaning sidewise, I have provided for two different levels therein. The levels 13^b, 14^b, are slightly above the 15 bottom wall of the runway and serve to support a coin when two coins attempt to roll side by side down the runway. As soon, however, as one coin passes ahead of the other both will travel on the floor of the 20 runway. By this arrangement it is possible to cause two or more coins to travel in the same runway without possibility of becoming jammed.

At the outlet from the runways I have 25 shown two forms of receiving devices. In the forms shown in Figs. 1, 2 and 4 the device constitutes a deflector whereby the coins are discharged flatwise onto a counter and consist of an inclined floor 26, side wall 30 27 and an inclined deflecting plate 28. The arrangement is such that as the coins roll edgewise out of the runways they contact the inclined plate 28 and are tipped and their motion arrested in such manner that 35 they slide down the inclined floor 26 onto the counter without danger of rolling away.

In the construction shown in Figs. 5 and 40 6 a simple cup is provided which is generally angular in form, the floor 29 being inclined downwardly to the receiving portion 30, which has a curved end wall 31 which assists in removing the coins from the cup. To make certain that the coins do not roll 45 edgewise down the floor 29 with such speed as to jump out of the cup, I provide the cross piece 32, spaced above the floor a distance less than the height or diameter of any of the coins. This causes the coins to fall flatwise into the cup. To prevent the coins 50 from jumping over the edge of the cup as they emerge from the runways, I provide the guard 33.

By the use of the construction shown, it 55 will be seen to be possible to select the coins as they are discharged from the paying machine, conduct them to the point of delivery without bringing them together, at which

point they may be either brought together or separately disposed of as desired.

I claim:

1. In coin handling mechanism, the combination of means for delivering coins in a substantially horizontal position, a plurality of narrow hoppers shaped to cause said coins to assume a vertical position, runways for 65 conducting coins to a remote point by allowing the same to roll on edge, certain of said runways being of a width sufficient to accommodate two coins, the floor of said runways being stepped whereby coins entering 70 said runways side by side are caused to roll at different elevations, substantially as described.

2. In coin handling mechanism, the combination of means for delivering coins, a 75 plurality of narrow hoppers one for each coin denomination, and a runway for each coin, one of said runways being provided with a stepped floor whereby two coins of the same denomination entering said runway are caused to travel on different levels to the point of discharge, substantially as described.

3. In a coin handling device, the combination of a plurality of runways mounted 85 horizontally beneath a delivering mechanism, and a delivery receptacle at the termination of said runways, an end wall of said receptacle being inwardly inclined with relation to the floor of the receptacle, the 90 wall being inclined in a direction from which the coins approach the wall whereby the coins are caused to lie flat on the floor of the receptacle, the floor being laterally inclined and open for the discharge of the coins at a 95 right angle to the direction from which they are received, substantially as described.

4. In a coin handling device, the combination of a plurality of runways, a delivery receptacle at the point of convergence of said runways, the floor of said receptacle being substantially flat and inclined laterally downwardly from the discharge point of said runways, an end wall of said receptacle being so constructed and inclined as to cause 100 the coins to fall flat and slide down the floor of the receptacle, substantially as described. 105

Signed at Chicago, Illinois, this 7th day of April, A. D. 1916.

EDWARD J. BRANDT.
